UNITED STATES PATENT OFFICE.

JOHN H. MONTSTREAM, OF HARTFORD, CONNECTICUT.

FLEXIBLE SHAFT-COUPING.

No. 801,672.

Specification of Letters Patent.

Patented Oct. 10, 1905.

Application filed February 27, 1905. Serial No. 247,413.

To all whom it may concern:

Be it known that I, JOHN H. MONTSTREAM, a citizen of the United States, residing at Hartford, in the county of Hartford and State of Connecticut, have invented a new and useful 5 Flexible Shaft-Coupling, of which the following is a specification.

This invention relates to a flexible shaft-coupling of the fork and block type, in which 10 the connecting-pieces are subjected to compressional and not shearing strains when in use.

The object of the invention is to provide a 15 simple coupling of this nature which is very strong and durable and which operates with a minimum amount of friction.

In this coupling the forks are so constructed and the blocks so shaped that the torsional strains of use are sustained by solid portions 20 of the block way out to the periphery of the coupling and the frictional or sliding surfaces under pressure are merely small sections of the peripheries of the pins which hold the forks to the block and are very small 25 in diameter, as they are only subjected to compression, and equally small sections of the pin-sockets in the forks.

Figure 1 of the accompanying drawings shows a side view of a coupling that embodies 30 the invention. Fig. 2 shows a transverse section of this coupling through the forks, the block, and the connecting-pins. Fig. 3 shows an end view of one fork. Fig. 4 shows an edge view of the block. Fig. 5 shows a face 35 view of the block, and Fig. 6 shows a side view of a modified form of this coupling.

The shaft ends 1 are duplicates and are provided with the usual means for fastening them to the ends of the shafts to be coupled. 40 Each shaft end has a fork 2. The fork-arms are considerably narrower than the spaces between them, and when together the back edges of the arms of the forks are close to each other and the front edges are separated 45 some distance.

The block 3, which is located between the forks, has segmental portions 4, that extend outwardly to the periphery of the coupling occupying the spaces between the front edges 50 of the opposing fork-arms. These segmental portions nearly fill the spaces between the front edges of the fork-arms, and small pins 5 are driven into the block between the edges of the segmental portions and the front edges 55 of the arms of the forks. It is preferred to recess the edges of the fork-arms and block,

so that the pins are partly in the edges of the fork-arms and partly in the edges of the segmental portions of the block. The edges of the block and the edges of the fork-arms are 60 cut away so as to allow free oscillation of the several parts.

When this coupling is in use, the torsional strains are transmitted through the pins to the segmental portions of the block, and as the 65 pins and these portions of the block entirely fill the spaces between the front edges of the fork-arms the pins and the portions of the block between the fork-arms are practically subjected only to compressional strains. For 70 this reason the pins may be made very small in diameter, and as the only surfaces which slide under torsional stress are the surfaces on the front edges of the fork-arms which oscillate on the peripheries of the pins the 75 amount of friction is very small. As the pins are backed by solid portions of the block and are only subjected to compression, much of the edges of the block may be cut away diametrically, so that the arms may be quite 80 thick, thus insuring strength and a long bearing on the pins. The pins arranged in this manner hold the shaft ends together, so that it is unnecessary to provide the shaft with 85 bearings adjacent to the coupling for the purpose of holding the parts together. The drive in a coupling of this construction extends way out to the periphery of the coupling, and the forks are so thick and bear against the pins 90 in such manner that they do not spring and cramp on the block when in use.

In the form shown in Fig. 6 the bearing edges of the segmental portions of the block are reduced nearly to knife-edges and the pins, which are preferably very hard, are 95 grooved to receive these narrow edges. This reduces the oscillating friction of the parts to a very small and practically inappreciable amount, and yet this coupling is strong and durable for the segmental portions of the block, and the pins completely fill the spaces 100 between the forks, which are quite thick.

The invention claimed is—

1. A flexible shaft-coupling comprising 105 shaft ends with forks, a block with portions extending between the opposing edges of the opposite fork-arms, and pins securing the fork-arms to the block, substantially as specified.

2. A flexible shaft-coupling comprising 110 shaft ends with forks, a block with portions extending between the opposing edges of the

opposite forks, and pins between the edges of the block and the opposing edges of the forks, substantially as specified.

3. A flexible shaft-coupling comprising shaft ends with forks arranged with the back edges of the fork-arms adjacent and the front edges of the fork-arms separated, and a block between the forks and having portions occupying the spaces between the front edges of the opposing fork-arms, substantially as specified.

4. A flexible shaft-coupling comprising shaft ends with forks, a block located between the forks, and pins driven into the block between portions of the block and the front edges of the opposing fork-arms, substantially as specified. 15

JOHN H. MONTSTREAM.
